UNITED STATES PATENT OFFICE.

MILTON L. CORNELL, OF NEW YORK, N. Y.

METAL ROLLING SHUTTER AND DOOR.

Application filed January 6, 1923. Serial No. 611,161.

To all whom it may concern:

Be it known that I, MILTON L. CORNELL, a citizen of the United States, and a resident of New York, in the county and State of New York, have invented certain new and useful Improvements in Metal Rolling Shutters and Doors; and I do hereby declare the following to be a full, clear, and exact description of the invention, such as will enable others skilled in the art to which it appertains to make and use the same.

This invention relates to metal rolling shutters and doors, and more particularly to such doors as are located on exterior openings to buildings, piers, boats, etc., and therefore exposed to the elements. These doors heretofore have usually been made of galvanized steel slats or corrugated sheets. The bottom of the doors are subject to unusual conditions due to collected rain water, sea water, banks of snow, etc., which render the bottom foot or two subject to accelerated corrosion not experienced by the upper portion of the door. The principal object of this invention therefore is the provision of means for rendering the lower portion of the door sufficiently resistant to corrosion to substantially increase its life, and hence the life of the entire door, and to do this without substantially increasing the cost of manufacture.

These doors usually comprise a plurality of interlocking steel slats which form flexible curtains, and in carrying my invention into effect with this form of door, I replace the lower steel slats by a material of greater weather-resisting, non-corroding properties.

A further object of the invention is the provision, in a door such as described in the preceding paragraph, of means for preventing electrolytic action between the dissimilar materials.

A further object of the invention is the provision of means for increasing the weather-resisting and non-corrosive properties of the lower portions of the usual guides in which the door slides.

Other objects and advantages will in part be obvious and in part be specifically referred to in the description which follows:

In the accompanying drawings,

Fig. 1 is a front elevation of a door embodying my invention.

Fig. 2 is a vertical section taken on the line 2—2 of Fig. 1.

Fig. 3 is a section taken on the line 3—3 of Fig. 1.

Fig. 4 is an enlarged section through a portion of the door curtain and the bottom bar.

Fig. 5 is a view similar to Fig. 4 showing a modified form of bottom bar.

Fig. 6 is a front elevation of a portion of the door curtain showing an end-lock.

Referring to the drawings, there is shown a flexible door curtain 10 of a usual type fixed at one end to a shaft 11 revolvably mounted in supporting brackets 12, said curtain being adapted to be raised or lowered either by handles on the bottom bar, or by the shaft 11 which may be revolved by a chain 13 running over a sprocket connected through gears in usual manner to the end of said shaft. The curtain may be composed of a series of interlocking, horizontally-disposed slats, as shown on a large scale in Figs. 4, 5, and 6. At its lower end the curtain is provided with a rolled steel beam or bottom bar which may be a single right-angle bar 14 as in Fig. 4, or the double right-angle bar 15 as in Fig. 5. The curtain is guided in its vertical movements by the usual channel shaped bars 16 in which the sides of the curtain extend and operate.

Where the slats are of galvanized steel and the bottom bar and guide-bars are of the usual black steel painted, it is found that the lower foot or so of these members above the ground is rapidly corroded and destroyed, for the reasons hereinbefore referred to. To obviate this condition, I substitute for a number of the usual steel slats, at the bottom of the curtain, slats 20 composed of a non-corrodible metal, such as bronze, brass, zinc, or aluminum. Where these doors are subjected to frequent use and the lower slats are of brass, bronze or other copper alloy, the zinc coating of the galvanizing on the lower steel slat, where the latter joins the upper alloy slat, is liable to wear off, in which event the uncoated steel of this lower slat, and the connecting copper alloy slat, may be in contact and an electrolytic action may result, with a consequent hastening of corrosion of the steel.

To avoid this, I interpose an insulating slat, as indicated at 21, between the adjacent slats of the upper and lower series, 20 and 22. This slat may be of zinc, aluminum, 5 aluminum alloy, or other suitable metal electropositive to steel and hence protective to steel in the case of possible electrolysis, and which, because of the oxides which they readily form, greatly delay any electrolysis, but such insulating slat is necessary only where the lower slats 20 are of brass, 10 bronze or other copper alloy, or other metal which may readily hasten electrolysis in contact with steel. Similarly, where the lowest slat 20 joins the bottom bar 14 or 15, an insulating strip 23 of zinc, aluminum or hard fibre may be interposed. In addition, the bottom bar may be heavily galvanized.

The bottom portions 25 of the side guides 20 also will preferably be coated with zinc as indicated at 26 in Fig. 1, as a further protection against corrosion of these parts. This coating is preferably put on by the hot dipped process, but any other well known 25 method of zinc coating steel may be used. As the curtain does not fit closely in the guides, the zinc coating should be the only insulation necessary at these places.

Each alternate slat is usually fitted at 30 each end with an end-lock 30, so that at least one edge of each slat is held at both sides against lateral movement. These end-locks serve also to prevent contact and friction of the sides of the curtain in the guides. Such 35 end-lock is usually a casting, in which case the "skin" which is formed thereon in the casting process serves to resist corrosion. It is often desirable that the material of the end-locks be the same as that of the slats 40 to which they are fastened, or of some insulating material, to prevent electrolysis. These end-locks may be fastened to the respective slats by rivets 31 passing through flanges 32 integral with the locks. The 45 rivets should be made of heavily galvanized steel or may be of the same material as the slats through which they pass, or of some insulating material such as zinc or aluminum, to prevent electrolysis.

50 The hereinbefore described structure provides a durable door or shutter in which the bottom parts wear longer than the upper parts and thus greatly increases the life of the door or shutter as a whole.

55 I have herein shown and described my invention in connection with a door or shutter, the curtain of which is made up of a plurality of interlocking slats, but such curtains in some cases are also made up of single 60 corrugated sheets, and it will be understood that my invention is equally applicable to curtains made up in this way.

It will be understood that various changes and modifications may be made within the

scope of the invention as defined in the annexed claims.

What I claim is:—

1. A door or shutter comprising an upper portion of relatively corrodible metal, and a lower structural portion of a metal of 70 relatively non-corrodible quality.

2. A door or shutter comprising an upper portion of ferrous material, and a lower structural portion of a non-corrodible metal. 75

3. A rolling door or shutter composed of a plurality of interlocking slats, the upper slats being formed of a relatively corrodible metal, and the lower slats being formed of a metal of relatively non-corrodible quality. 80

4. A rolling door or shutter composed of a plurality of interlocking slats, the upper slats thereof being formed of corrodible metal and the lower slats thereof being formed of non-corrodible metal, and insulating material connecting said slats of different metals. 85

5. A rolling door or shutter composed of a plurality of interlocking slats, the upper slats thereof being formed of corrodible 90 metal and the lower slats thereof being formed of non-corrodible metal, and a slat of insulating material connecting said upper and lower slats.

6. A rolling door or shutter composed of a plurality of interlocking slats, the upper slats thereof being formed of corrodible metal and the lower slats thereof being formed of non-corrodible metal, a bottom bar connected to the lowest slat, and insulating material between said bottom bar and said lowest slat. 95

100 7. A rolling door or shutter composed of a plurality of interlocking slats, the upper slats thereof being formed of corrodible 105 metal and the lower slats thereof being formed of non-corrodible metal, insulating material connecting said slats of different metals, a bottom bar connected to the lowest slat, and insulating material between said 110 lowest slat and said bottom bar.

8. A rolling door or shutter composed of a plurality of interlocking slats, the upper slats thereof being formed of corrodible 115 metal and the lower slats thereof being formed of non-corrodible metal, a slat of insulating material connecting said upper and lower slats, a bottom bar connected to the lowest slat, and insulating material between said 120 lowest slat and said bottom bar.

9. A rolling door or shutter composed of a plurality of interlocking slats, the upper slats thereof being formed of corrodible metal and the lower slats thereof being formed of non-corrodible metal, side guides 125 of corrodible metal in which said shutter operates, and means for rendering the lower portion of said guides non-corrosive.

10. A rolling door or shutter composed of a plurality of interlocking slats, the upper slats thereof being formed of corrodible metal and the lower slats thereof being formed of non-corrodible metal, a slat of insulating material connecting said upper and lower slats, a bottom bar connected to the lowest slat, insulating material between

said lowest slat and said bottom bar, side guides of corrodible metal in which said 10 shutter operates, and means for rendering the lower portion of said guides non-corrosive.

In testimony whereof I affix my signature.

MILTON L. CORNELL.
